UNITED STATES PATENT OFFICE.

GREGORY H. SCHAFER, OF YPSILANTI, MICHIGAN, ASSIGNOR TO THE SCHAFER SMOKE PREVENTER COMPANY, OF YPSILANTI, MICHIGAN.

DRAFT-REGULATOR FOR FURNACES.

1,170,683.

Specification of Letters Patent.

Patented Feb. 8, 1916.

Application filed December 30, 1911. Serial No. 668,596.

To all whom it may concern:

Be it known that I, GREGORY H. SCHAFER, a citizen of the United States of America, residing at Ypsilanti, in the county of 5 Washtenaw and State of Michigan, have invented certain new and useful Improvements in Draft-Regulators for Furnaces, of which the following is a specification, reference being had therein to the accompanying drawings.

My invention relates to new and useful improvements for draft regulators for furnaces and to that type of regulator whereby upon the opening of the fuel feed door of 15 the furnace, a steam jet which is positioned to discharge across and above the fuel, is turned on, the steam discharging into the furnace cylinders when the door is open and being gradually shut-off after the door 20 is closed.

The invention resides in the novel arrangement of the steam jet, in the peculiar construction of the operating connection, and in certain combinations, arrangements 25 and constructions of various parts as will be more fully hereinafter described and particularly pointed out in the claims.

In the drawings, Figure 1 is a front elevation of a furnace with my invention applied thereto; Fig. 2 is a fragmentary vertical section through the structure of Fig. 1; Fig. 3 is a central section through the dash pot, and Fig. 4 is a detail view, partly 35 in section, of the valve controlling the supply of steam to the furnace.

A designates the boiler front, B and C the fuel doors, and D the supply pipe for the steam jets or nozzles.

E are dampers for the doors pivoted 40 thereto at F, and G is a rock shaft journaled above the doors in bearings H on the boiler front. This rock shaft is connected to the dampers by means of links I each having its opposite ends pivoted respectively to a lug J on the damper and an arm K on the shaft G. The arm K is formed integral with a collar L which has a longitudinal and rotative adjustable engagement with the shaft, the collar being held in its adjusted 45 position by a set-screw L', and the pivots for the opposite ends of the link are arranged substantially at right angles to the hinge connection for the door. This arrangement causes the link and arm to effect a rocking of the shaft G upon the open-

ing of the door and permits the collar to be adjusted lengthwise of the shaft so as to vary the degree of movement of the latter.

N is a rod pivoted at its lower end to a rock arm O and similarly connected at its upper end to an arm P intermediate the ends of the latter. Pivotedly connected to one end of the arm P is a piston rod Q of a dash pot R, while the opposite end of this arm is secured to the lever T of the valve U which controls the steam supply pipe D. The arm O is adjustable in relation to the shaft G and is secured in its adjusted position by a set-screw D'.

With the construction described, upon the opening of the door the shaft G will be rocked, which will actuate the rock arm O and raise the rod N. The raising of the rod will lift the piston of the dash pot and also operate the valve lever to open the valve 70 and admit steam to the supply pipe. When the doors are closed the dash pot will retain the rod in its raised position, which will prevent the shaft G from rocking, thereby effecting an opening of the dampers. As 75 the piston of the dash pot descends the shaft G and the arm O will be rocked, permitting the valve on the dampers to be gradually closed.

It will be noticed that the connection between the various parts is such as to effect a positive operation thereof in both the opening and closing movement. The desired relative movement between the piston of the dash pot and the fuel doors may be obtained 80 by adjusting the arms K and O.

In Fig. 3 I have illustrated a novel construction of dash pot which is particularly adapted for controlling the closing of the dampers and the steam valve. As shown, A' designates the cylinder which is provided 85 with brackets B' that are attached to the front A. C' is an enlargement at one side of the cylinder which has a by-pass D² communicating by means of a bore E' with the cylinder chamber at the bottom thereof and provided adjacent the top with an opening F' leading within the cylinder. Above this opening is an aperture G' also extending 90 through the cylinder wall. The opening F' is controlled by an inlet valve H' while the aperture G' is normally closed by means of a valve I'. Preferably the piston is hollow 95 and has a spider K' at the top thereof provided with a bearing L² to which is secured 100

the rod Q. The bottom of the piston is formed with an opening M' therethrough, but the remaining portion of the bottom is imperforated. This opening is closed by a downwardly opening valve N' normally held to its seat through the medium of a spring P'. Q' is a spider for limiting the downward movement of the valve. Thus upon the upward movement of the piston the fluid contained in the cylinder is free to pass up the valve N', but upon the downward movement of the piston the valve N' will be closed, which forces the liquid through the restricted passage D' and out through the opening F'. R' is a recess formed in the side wall of the cylinder and leading from the opening F' to the top of the piston. Thus in case the piston is raised above the opening F' communication will be provided between the passage D' and the portion of the cylinder above the piston. In case it is desirable to permit the piston to immediately descend upon the closing of the door, the valve I' is adjusted to open the passage G'. The speed with which the piston descends may be varied by adjusting the inlet valve H'. Preferably a strainer S' is arranged within the passage D'.

Heretofore the nozzles or steam jets have been positioned in apertures formed through the brickwork above the fuel doors, but this arrangement has been found to be very objectional since by so locating the jets the latter are subjected to an intense heat and would frequently crystallize and break off when steam was introduced therethrough. Furthermore, when extended through the brickwork the condition of the jets could not be ascertained without completely removing the latter. By my invention the jets a b are arranged within the door openings adjacent the top thereof, the jets being supported solely by a horizontal branch c of the steam supply pipe and being out of contact with the furnace walls. d is a bracket on the boiler front for securing the horizontal branch in place. Preferably the jets have a swiveled engagement as at e with couplings f in the branch c and the nozzles proper g have a detachable screw-threaded engagement with elbow joints h. Character i are recesses in the top of the doors for receiving the jets when the doors are closed. With this arrangement the jet is in view when the fuel door is open, while the swivel connection permits the jet to be turned outward so that the nozzle may be readily detached and a new one replaced when required. Furthermore, the nozzle is not subjected to the intense heat that it would be if extended through the wall of the boiler front, and as it is not necessary to drill holes through the front wall my improved device may be applied to a furnace when the latter is in operation.

In order to insure the full closing of the

damper and the valve, the passage D' is provided with an unrestricted port T', which is normally closed by the piston but is so positioned that when the piston is at the downward limit of its movement the port 70 will be uncovered, thereby permitting any oil in the bottom of the cylinder to pass through the port T'.

What I claim as my invention is—

1. In a draft regulator for furnaces, the 75 combination with a damper of a fuel door, a steam-supply pipe, a jet leading from the pipe within the furnace, a valve controlling the admission of steam to the jet, a rock shaft, a rock arm fixed to the shaft, a rigid 80 rod having the opposite ends thereof pivotally connected respectively to the arm and the damper, whereby upon the opening of the fuel door the rod will be actuated by the chamber to rock said shaft, a second rock 85 arm secured to the shaft, a rod having one end pivoted to the latter arm, a connection 90 between the other end of the rod and the valve, and a timed retarding device for controlling the closing of the damper and the valve upon the closing of the fuel door.

2. In a furnace, the combination with a 95 valve or damper of means for operating the same in one direction and a retarding device for controlling movement thereof in the opposite direction, comprising a cylinder, a piston therein, a passage communicating with the cylinder at the bottom thereof, a restricted port leading from the 100 passage to the interior of the cylinder adjacent the top thereof, an opening above said port also forming a communication between the passage and the interior of the cylinder, and a normally closed valve controlling said port.

3. In a draft regulator for furnaces, the 105 combination of a damper of a fuel door, a steam supply pipe, a jet leading from the pipe within the furnace, a valve controlling the admission of steam to the jet, positively connected levers of fixed length connecting the damper and the valve including a rockable member, a rigid rod of fixed length secured to said member and said damper, whereby upon the opening of the damper 110 said member will be rocked, a rod attached to said rockable member and operatively secured to said valve, and a timed retarding device for controlling the closing of the 115 damper and valve.

4. In a draft regulator for furnaces, the 120 combination of a valve or damper, of means for operating the same in one direction and a retarding device for controlling movement thereof in the opposite direction, comprising a cylinder, a piston therein having an opening in its bottom, a valve controlling 125 said opening, a spring normally closing said valve arranged within the piston, a spider carried by the piston for limiting the open-

ing movement of the valve, and a restricted passage permitting the flow of fluid from the chamber on one side of the piston to the chamber on the opposite side when the piston is moved in one direction.

5. In a draft regulator, the combination with a valve or damper, of means for operating the same in one direction and a retarding device for controlling movement thereof in the opposite direction, comprising a cylinder, a piston therein, a restricted passage permitting the flow of fluid from the chamber on one side of the piston to the chamber on the opposite side when the piston is moved in one direction, an unrestricted port permitting passage of the fluid from one of said chambers to the other when the piston is moved in the opposite direction, and means for forming a substantially unrestricted conduit out of said restricted passage.

6. In a furnace, the combination with a valve or damper, of means for operating the same in one direction and a retarding device for controlling movement thereof in the opposite direction, comprising a cylinder, a by-pass communicating with the cylinder

adjacent the bottom thereof and leading to adjacent the top of the cylinder, a piston having an opening in its bottom, and a 30 spring-pressed valve normally closing said opening, the side wall of the cylinder being provided with a recess leading to the top of the cylinder, for the purpose described.

7. In a draft regulator for furnaces, the 35 combination with a valve or damper, of means operating the same in one direction and a retarding device for controlling movement thereof in the opposite direction, comprising a cylinder, a piston within said 40 cylinder having an opening in its bottom, a valve controlling said opening, a spider carried by said piston for directly limiting the opening movement of said valve, and restricted means of communication between 45 the chambers on opposite sides of the piston when said piston is moved in one direction.

In testimony whereof I affix my signature in presence of two witnesses.

GREGORY H. SCHARF.
